DESIGN FOR A VENTILATOR FOR BUILDINGS

Charles S. Warnock, Los Angeles, Calif.

Application September 24, 1941, Serial No. 103,468

Term of patent 7 years

To all whom it may concern:

Be it known that I, Charles S. Warnock, a citizen of the United States and a resident of Los Angeles, Los Angeles County, California, have invented a new, original, and ornamental Design for Ventilators for Buildings, of which the following is a specification, reference being had to the accompanying drawing, forming a part thereof.

Fig. 1 is a side elevational view of a ventilator for buildings showing my new design; and

Fig. 2 is a top plan view thereof.

I claim:

The ornamental design for a ventilator for buildings, as shown.

CHARLES S. WARNOCK.
